Lacey Lacey, Attorney

UNITED STATES PATENT OFFICE

FRANK CLARK, OF DOLIVER, IOWA

REVERSIBLE SIFTER

Application filed September 25, 1928. Serial No. 308,359.

The invention relates to household implements and more particularly to a utensil for use in the kitchen in the preparation of food.

Specifically considered, this invention applies to a flour sifter and provides an article in which the screen is reversible so that the flour may be sifted as many times as desired without necessitating its removal from the sifter, the latter being reversed after each sifting of the flour.

The invention contemplates a sifter embodying a container for receiving the flour, a reversible screen, an agitator for stirring the flour to insure its passage through the screen, and instrumentalities for mounting the screen and agitator and reversing the screen and securing it in either extreme position.

While the drawings illustrate a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof reference is to be had to the following description and the drawings hereto attached, in which:

Figure 1 is a vertical central sectional view of a household sifter embodying the invention.

Figure 2 is a horizontal sectional view.

Figure 3 is a detail perspective view showing more clearly the means for securing the covers to the ends of the body.

Figure 4 is a transverse sectional view of the screen and a portion of the body.

Corresponding and like parts are referred to in the following description and designated in the several views of the drawings by like reference characters.

The numeral 1 denotes the body or container for receiving the flour or other articles to be sifted. The part 1 is open throughout its length and may be of any determinate outline in cross section. A cover 2 closes each end of the body 1 and is retained in place

by suitable fastening means 3 which, as shown, consist of hooks pivoted on opposite sides of the body 1 and engageable with portions of the covers by passing through slits formed therein, as indicated at 4 in Figure 5 of the drawings. In this manner, casual displacement of the covers is prevented.

A short tubular extension 5 projects laterally from the body or container 1, intermediate its ends and constitutes a bearing for a plug 6 which is fitted at its outer end. The plug 6 is free to turn and move longitudinally in the extension 5 and is provided at its inner end with pins 7 which are fitted within openings 8 of the screen, whereby to cause the screen and plug to turn in unison when it is required to reverse the screen. Notches 9 are formed in the outer end of the extension 5 and receive pins 10 projecting laterally from opposite sides of the plug 6. When the plug 6 is drawn outwardly to a distance to disengage the pins 10 from the notches 9, it may be turned in either direction to reverse the screen which, as stated, is connected to the plug by means of the pins 7 and openings 8. When the screen has been properly positioned it is held by moving the plug 6 inwardly to cause the pins 10 to enter the notches 9.

The screen 11 is formed with a half-round bottom and straight ends, the latter converging slightly toward the bottom, as indicated most clearly in Figure 1 of the drawings, to provide spaces for the discharge of the flour during the sifting thereof. The body of the screen is formed of wire fabric of close mesh and is reinforced at its top by means of a metal binding 12 in which the openings 8 are formed. The top of the screen obtains a snug fit within the body or container 1 and said screen is free to turn by reason of the half-round formation of its bottom, as indicated most clearly in Figure 4 of the drawings.

An agitator or stirred 13 is disposed within the screen to effect a positive feed of the flour during the sifting thereof. This agitator includes or is mounted upon a shaft 14 which passes loosely through the ends of the screen and is mounted in the plug 6 and the opposite wall of the body 1. The end of the shaft 14 projecting beyond the plug 6 is formed with

5 a crank 15 which provides convenient means for rotating the agitator. The crank 15 provides a stop to limit the outward movement of the plug 6 and prevents disengagement of the pins 7 from the openings 8.

10 When using the sifter, the flour or other article is placed within the upper portion of the body. After the covers 2 have been placed in position they are made secure by means of the catches or fastenings 3. Upon rotating 15 the agitator by means of the crank 15, the flour is caused to sift through the screen and upon reversing the latter and the body, the flour may be sifted a second time and as often as desired by reversing the screen and the body after each operation of sifting. The flour is discharged by detaching the lower cover, as will be readily comprehended.

15 What is claimed is:

20 1. A household sifter comprising a body, a tubular extension projecting from a side of the body, a reversible screen within the body, a plug slidably connected with the screen and slidably and rotatably mounted in the said 25 tubular extension, and inter-engaging means between the plug and tubular extension for securing the screen in either extreme position.

20 2. A household sifter comprising a body, a tubular extension projecting laterally from the body intermediate the ends thereof, a reversible screen within the body, a plug rotatable and slidably mounted in said tubular extension and having pins carried thereby slidably coupled to the screen to effect a turning 35 thereof, interengaging means between the plug and tubular extension for securing the screen in the located position, and an agitator in cooperative relation with the screen and having a shaft which is mounted in the said 40 plug.

45 In testimony whereof I affix my signature.
FRANK CLARK. [L. S.]
